ATTACHMENT FOR ELECTRIC FIXTURES

Alexander K. Sutherland, Sheboygan, Wis., assignor to Moe-Bridges Corporation, Sheboygan, Wis., a corporation of Wisconsin

Application December 13, 1940, Serial No. 369,973

5 Claims. (Cl. 248—343)

This invention relates to attachments for electric fixtures, such as lighting fixtures, and has among its objects an attachment which permits quick and easy attachment of an electric fixture to a ceiling or other wall support, and enables simple mounting and adjustment of an attachment covering, such as a canopy, for covering up the interengaging portions of the attachment and the electric fixture connections.

The foregoing and other objects of the invention will be best understood from the following description of exemplifications thereof illustrated in the accompanying drawings, wherein

Fig. 1 is a vertical sectional view of a lighting fixture attachment to the ceiling of a room exemplifying one form of the invention;

Fig. 1a is a vertical cross-sectional view of a portion of the attachment;

Fig. 1b is a vertical sectional view along line 1b—1b of Fig. 1a;

Fig. 2 is a view similar to Fig. 1 illustrating another exemplification of the invention;

Figs. 3 to 5 are views similar to Figs. 1 to 1b illustrating another exemplification of the invention;

Fig. 6 is an elevational view of the fixture mounting rod shown in Fig. 3;

Fig. 7 is a perspective view of the clamping collar shown in Fig. 3;

Fig. 8 is a view similar to Fig. 1 illustrating another exemplification of the invention; and

Fig. 9 is a vertical sectional view showing the clamping members of Fig. 8.

In attaching or mounting an electric fixture, such as a lighting fixture, on a ceiling or other wall of a room, provision must be made not only for safe mounting of the fixture in its location, but also for easy accessibility to the electric splice connection between the fixture cord and the supply cord as well as proper covering up of the unsightly elements of the attachment and the electric cord connection of the fixture to the wall outlet.

The person mounting a fixture on the ceiling has usually to stand high up on a flimsy support, such as a ladder, and the problem of mounting or removing an electric fixture in its assembled position on its ceiling support is quite troublesome.

The invention provides a simple, foolproof and cheap attachment for an electric lighting or similar fixture which permits easy and quick mounting and adjustment of the fixture in its location and the splicing of its cord connections to the wall outlet cord as well as the easy, quick

and simple mounting and adjustment of the cover member or canopy overlying the attachment elements and the cord connections in its final assembled condition.

Fig. 1 illustrates an exemplification of the invention in the form of a suspension attachment for a lighting fixture mounted on a ceiling of a room. The lighting fixture, not shown on the drawing, has an upward extension in the form of a suspension chain 10 and a cord 11 which are attached and connected respectively to a fixture support formed of a threaded supporting stud 12 and electric outlet leads 13 located in an outlet box 14 provided in the ceiling.

The chain 10 which forms a part of the upward fixture extension, is shown suspended on a cap 15 of a mounting rod 16 which is clamped by segmental gripping members in the form of clamping jaws 17 held and guided on the inner tubular surfaces of a supporting sleeve member 18 extending from the supporting stud 12 and shown threadedly joined thereto. The splice connection of the fixture cord 11 to the outlet cord 13 as well as the unsightly elements of the attachment are covered by a cover member in the form of a canopy 20 of sheet metal which is held against the wall of the ceiling by a collar 21 which is threadedly mounted on the exterior surface of the rod cap 15.

As illustrated in Figs. 1 to 1b, the lower portion of the fixture supporting sleeve member 18 has an inwardly tapered conical guide surface 22 for guiding thereon the exterior surfaces of the jaw-like segmental gripping members 17 into clamping engagement with the mounting rod extension 16 of the fixture. The jaw-like gripping members 17 have interlocking projections in the form of toothed surfaces 23 shaped for interlocking engagement with interlocking teeth formed on the exterior of the mounting rod 16.

The facing teeth of the jaw-like gripping members 17 and the fixture mounting rod 16 are tapered in the inward and outward direction of the motion of the mounting rod 16 in the supporting sleeve 18, and are so arranged that when the fixture supporting rod 16 and the gripping members 17 are moved in inward direction relatively to the supporting sleeve 18, the segmental gripping members 17 are actuated to move outwardly along the tapered inner guide surface 22 of the supporting sleeve 18 so as to break the clamping engagement between the toothed surface 23 of the gripping members and the fixture supporting rod 16, and release the latter for removal from the supporting sleeve

10. The tapered inner guide surface 22 of the supporting sleeve 18 with the facing outer guide surfaces of the gripping members 17 are so shaped that when said gripping members are moved longitudinally along their guide surfaces in outward direction, the inner guide surface 22 of the supporting sleeve 18 actuates the gripping members to bring their inwardly facing interlocking teeth 23 into interlocking engagement with the teeth of the fixture mounting rod 16.

15. The interlocking teeth formed on the fixture mounting rod 16 and the facing toothed surfaces 23 of the segmental gripping jaw member 17 may be of any desired form as long as the interlocking teeth are tapered in inward as well as in outward direction in relation to the direction of the longitudinal motion of the fixture mounting rod 16 as it is moved inwardly or outwardly out of its position in the mounting sleeve 18.

20. In the form shown, the interlocking teeth are formed by providing the fixture mounting rod 16 with a screw threaded exterior surface, and by forming the segmental gripping members 17 out of two halves of a split nut member having inwardly facing threads corresponding to the external threads of the rod 16 so as to assure positive clamping engagement between the fixture mounting rod 16 and the interlocking surfaces 23 of the clamping jaws 17 when the latter are biased inwardly toward the rod by externally acting forces, such as the gravity forces.

25. As shown, the lower outer surface portions of the gripping members 17 are tapered and shaped for sliding movement on the lower tapered guide surface of the supporting sleeve 18 so that on pushing the exposed downwardly protruding ends 24 of the gripping jaws 17 in upward direction, the jaws are moved in radially outward direction and release their threaded toothed surface portions 23 from the clamping engagement with the toothed surface of the mounting rod 16, in the way shown in Figs. 1a and 1b to enable quick partial or complete withdrawal of the mounting rod 16 from its location between the jaws 17. The upward motion of the clamping jaws is suitably limited as by a stop washer 25 suitably clamped between the walls of the sleeve 18.

30. Since the upper ends of the leads of the electric cord 11 of the lighting fixture have to be connected to the outlet leads 13 within the canopy 20, it is essential to assure that the leads of cord 11 cannot be caught by the teeth of the fixture supporting rod 16 or otherwise damaged by them when it is pushed upwardly into its finally assembled position between the clamping segment jaws 17 of the fixture support.

35. In the arrangement shown, damage to the leads of cord 11 and catching of a cord in the teeth of the mounting rod 16 is positively prevented by surrounding the portion of the mounting rod 16 extending within the canopy with a flexible elastic guard member 26 which keeps the cord leads away from the toothed mounting rod 16, while permitting tools, such as pliers, or the fingers, to reach the mounting rod 16 and the lower ends 24 of the clamping jaws 17 for removing the fixture from its position.

40. In the form shown in Fig. 1, the guard member is formed of a helically wound flexible wire spring 23 having its lower end 27 clamped around the lower end of the threaded mounting rod 16 at the point where it emerges from its threaded engagement with the rod cap 15. Alternatively, the guard member may be formed of a sleeve 28 of thin flexible rubber-like material surrounding the

45. mounting rod 16, in a way similar to the helical spring 26, the lower end of the sleeve having a small narrow opening clamped tightly to the lower portion of the mounting rod 16 at the point where it emerges from the rod cap 15.

50. In order to mount the fixture in its place on the ceiling, the supporting sleeve 18 with the gripping jaws 17 held therein is first mounted on the ceiling stud 12. The upper end of the mounting rod is then inserted between the lower ends of the clamped jaws 17 and left clamped therein while the ends of the cord 11 and the outlet leads 13 are spliced. Thereupon, the mounting rod 16 with the canopy 20 supported on the collar of the rod cap 15, in the way shown by the dotted lines 15', 20', 21', is pushed upwardly between the radially displaced jaws 17 until the fixture attachment is brought to its assembled position, with the upper edge of the canopy 20 resting against the ceiling.

55. Upon releasing the clamping rod 16, the outwardly acting forces exerted by the weight of the light fixture will, through the interlocking engagement between the teeth of the mounting rod 16 and the teeth of the jaws 17 engaged thereby, pull the clamping jaws 17 in downward outward direction and force them along the tapered guide surface 22 of the supporting sleeve to their radially inward clamping position so as to firmly clamp the fixture rod 16 and the canopy 20 in their assembled full-line position shown in Fig. 1. Any small gap left between the upper edge of the canopy 20 and the ceiling may be closed by turning the canopy collar 21 on the exterior threaded flange of the rod cap 15.

60. The simple fixture attachment described above enables not only simple, easy and quick mounting and adjustment of the fixture in its position on the wall without any tools, but also permits quick complete removal of the fixture or its temporary release from its assembled position for inspection or repair of the cord connections, while the fixture and its canopy 20 are suspended in the lowered dotted-line position 20'. Thus, in order to temporarily lower the fixture, the canopy collar is first unscrewed to release the canopy 20 and let it slip down the chain 10. Thereupon, the cord guard 26 is pushed downwardly while the lower protruding ends 24 of the clamping jaws 17, together with the mounting rod held between them, are pushed inwardly within the mounting sleeve 18 so as to spread the jaws 17 apart and release the clamping rod 16 which, thereupon, may be either entirely withdrawn for complete removal of the fixture, or merely left suspended with its upper end clamped between the clamping jaws in their downward clamping position. The fixture may be quickly restored to its assembled position by merely pushing the clamping rod 16 to its upward position, the canopy 20 being first placed in its position on the cap 15 by its threaded collar 21.

65. A fixture provided with a fixture support arranged in the way described above may be thus readily raised and lowered at will to any convenient position, without any tools or implements, for inspection or repair and all parts may be easily and quickly adjusted in their proper positions with great ease.

70. In Figs. 3 to 7 is shown another exemplification of the invention. On a ceiling stud 12 is mounted a supporting sleeve 18A which guides on its inner surface two clamping jaws 17, two upwardly bent stop lugs 37 of the sleeve limiting 75 the upward motion of the jaws 17. Between the

jaws 17 is held clamped a mounting rod extension 16A having a cap 15A on which is suspended a chain 10 of a lighting fixture, not shown in the drawings.

The splice connection of the fixture cord 11 to the outlet cord 13 as well as the unsightly attachment elements are covered by a cover member in the form of a canopy 20A which is held in its location against the ceiling by a clamping collar 21A which has inwardly projecting bayonet lugs 32 forming helical slots engaging bayonet projections 33A provided on the periphery of the cap so that a turn of the clamping collar 21A forces the upper edge of the canopy 20A against the ceiling.

As illustrated in Figs. 3 to 5, the clamping jaws 17 form halves of the split nut having inner threaded surface portions 19 engaging the threaded surface of the mounting rod 16A so as to assure positive clamping engagement between the extension rod and the clamping jaws 17 when the jaws are pressed inwardly toward the rod by the downward forces of the weight of the fixture. The outer surfaces of the jaw members 17 are tapered and shaped for sliding movement on the lower tapered end of the supporting sleeve 18A, so that on pushing the threaded rod extension 16A in upward direction, the jaws 17 may spread apart and break the clamping engagement of their inner surfaces with the threaded surfaces of the clamping rod till the rod has been brought to its innermost position in which it holds the canopy 20A against the ceiling.

In order to mount the fixture, the supporting sleeve 18A is mounted on the ceiling stud 12 and the end of the mounting rod 16A is pushed in between the clamping jaws 17 so as to retain it in a downward position giving access to the ends of the cords 11 and 13 and permitting splicing of the exposed cord ends.

Thereupon, the mounting cap 15A and its rod 16A are pushed upwardly between the clamping jaws 17 until the upper edge of the canopy 20A has been brought against the ceiling. Upon releasing the clamping cap 15A, the downward forces acting on the clamping rod and the clamping jaws 17 will force the clamping jaws 17 to their radially inward clamping position between the tapered wall of the guide sleeve 18A so as to firmly clamp the fixture and the canopy 20A in their properly assembled position. Any small gap left between the edge of the canopy and the ceiling may be closed by a twist of the canopy mounting collar 21A on its bayonet engagement with the cap 15A.

The fixture attachment described above makes possible easy release of the coupling engagement between the clamping jaws 17 and the clamping rod 16A of the lighting fixture so as to permit inspection of, or changes in, the cord connections. This may be done in the way described in connection with Figs. 1 to 1b, by first releasing the canopy 20A and then pushing with the fingers the downwardly protruding end portions 19 of the clamping jaws 17 in upward direction along their tapered guide surfaces so as to release the clamping rod 15A and permit its complete withdrawal or lowering to a downward position.

Alternatively, the clamping rod 16A may be provided with a loosely mounted release sleeve 38 having a downwardly projecting lifting finger 39. The release sleeve 38 is so arranged that when it is pushed upwardly by the finger 39

5 while a lifting force is applied to the mounting cap 15A, the sleeve 38 pushes the lock jaws 17 in outward and upward direction along the tapered guide surface of the supporting sleeve 18A so as to break the clamping engagement of the clamping jaws 17 with the mounting rod 16A and permit lowering or withdrawal of the clamping screw from its position between the clamping jaws 17.

10 Depending on the applications, the mounting rod 16A may be made sufficiently long to permit splicing of the cord ends while the canopy 20A is mounted in its position on the mounting cap 15, in which case the mounting collar 21A may be omitted, and final adjustment of the canopy against the ceiling secured by a turn of the mounting cap 21A and its threaded rod 16A on the threads of the clamped split nut jaw members 17.

15 In Figs. 8 and 9 is shown another exemplification of the invention. On a ceiling stud 12 is mounted a supporting sleeve 41 which houses and guides in its lowered tapered end portion two movably positioned split nut clamping jaws 42 which are limited in their motion by a stop ring 43 held clamped within the sleeve 41. The clamping jaws 42 have threaded inner portions 43 shaped for clamping engagement with the threaded surface of a fixture mounting rod 45 20 extending from a swivel socket member 46 having a swivel socket seat 47 on which is suspended a swivel ball 48 of a lighting fixture extension 49.

25 The end of a fixture cord 50 extending through a hollow channel in the fixture extension 49 and the swivel ball 48 is suitably spliced to the end of the outlet cord 13 extending from the ceiling. A canopy 52 is clamped against the ceiling by a collar 53 which is held by a bayonet connection on bayonet projections 55 of the swivel socket member 46. As shown in Fig. 9, the mounting rod 45 may have a hollow passage 30 through which the end of the fixture cord 50 may be led by way of the openings 54 in the supporting sleeve to the point of its splice connection to the outlet cord 13.

35 The clamping rod may be provided with a loosely mounted release sleeve 56, having a lifting finger 57 projecting through a hole in the canopy 52. The lower ends of the clamping jaws 42 may be provided with inner upper tapered surfaces 58 shaped for engagement with the bottom surface of the tapered extension 59 of the stop ring 43, so that on pushing the clamping jaws 42 in upward direction they are spread radially apart to break their clamping engagement with the mounting rod 45. In addition, the bottom ends of the clamping jaws may be provided with tapered surfaces 60 for engagement with a correspondingly tapered end surface of the release sleeve 56 so that on pushing the release sleeves 56 in upward direction, its tapered upper surface 61 spreads apart the clamping jaws 42 to break their clamping engagement with the clamping rod. With this arrangement, upon lifting of the release ring 56, its tapered portion 61 spreads apart the tapered lower ends of the lock jaws 42 while their upper tapered surfaces 58 are spread apart by the tapered extension 59 of the lock ring 42 so as to break their clamping engagement with the clamping rod 45 and assure instantaneous release of the clamping rod.

40 45 50 55 60 65 70 75 The fixture mounting supports of Figs. 3 and 8 may likewise be provided with cord guards, such as 26 to 28 described in connection with Figs. 1

and 2, in order to assure that an electric cord lead is not caught and damaged by the teeth of the mounting rod when it is pushed inward in the jaws.

Instead of using internally threaded split nut clamping jaws for quickly breaking or automatically establishing the clamping engagement with threaded rods, other types of easily releasable and automatically acting clamping arrangements may be used. Furthermore, attachments of the type 10 described herein may be utilized with great advantage in connection with many other types of electric fixtures which have to be mounted on a wall or similar place.

The term "teeth" as used in the specification and claims to describe the interlocking projections on the exterior of the mounting rod and the facing surfaces of the gripping members, is intended to be descriptive of the projections formed by the individual screw threads, such as the threads on the mounting rod 18 or any other form of interlocking projections operating in a manner analogous to projections formed by the threaded surfaces of the mounting rod 18 and the facing surfaces of the gripping member 17.

The principles of the invention explained in connection with specific exemplifications thereof will suggest to those skilled in the art many other applications and modifications of the same. It is accordingly desired that the appended claims be construed broadly, and that they shall not be limited to the specific details shown and described in connection with exemplifications thereof.

I claim:

1. In an arrangement for attaching an electric fixture to a wall portion having exposed electric outlet leads, an elongated rod-like fixture extension having teeth on its external surface, and an electric fixture cord extending along said fixture extension; a hollow fixture support extending from said wall portion having an open outward end and interior guide surface portions surrounding said fixture extension; said interior guide surface portions being tapered interiorly in the direction toward the open end of said support; means for detachably and adjustably securing said fixture extension within said hollow support comprising a plurality of segmental gripping members biased to move along said guide surface portions of said support toward its open end and having teeth shaped to interlockingly engage the teeth of said extension and arranged so that said gripping members can be pushed inwardly along said guide surface portions for releasing their interlocking engagement with said extension; the teeth of said extension and the facing teeth of said gripping members being tapered in the directions of the inward and outward motion of said extension within said support; an enclosure carried by said fixture extension for enclosing the space in front of said mounting wall portion and covering the interengaging portions of said fixture extension, said fixture support and the connections between said fixture cord and said outlet leads; and means including a yieldable guard member interposed between the external extension surface and said electric cord for preventing said cord from reaching said external extension surface; said guard member being elastically flexible so that it may be readily displaced by an external force from its position between the cord and said external extension surface while maintaining its normal position in absence of external displacing forces.

2. In an arrangement for attaching an electric fixture to a wall portion having exposed electric outlet leads, an elongated rod-like fixture extension having teeth on its external surface, and an electric fixture cord extending along said fixture extension; a hollow fixture support extending from said wall portion having an open outward end and interior guide surface portions surrounding said fixture extension; said interior guide surface portions being tapered interiorly in the direction toward the open end of said support; means for detachably and adjustably securing said fixture extension within said hollow support comprising a plurality of segmental gripping members biased to move along said guide surface portions of said support toward its open end and having teeth shaped to interlockingly engage the teeth of said extension and arranged so that said gripping members can be pushed inwardly along said guide surface portions for releasing their interlocking engagement with said extension; the teeth of said extension and the facing teeth of said gripping members being tapered in the directions of the inward and outward motion of said extension within said support; an enclosure carried by said fixture extension for enclosing the space in front of said mounting wall portion and covering the interengaging portions of said fixture extension, said fixture support and the connections between said fixture cord and said outlet leads; and a helical guard member interposed between the external extension surface and said electric cord for preventing said cord from reaching said external extension surface; said guard member being elastically flexible so that it may be readily displaced by an external force from its position between the cord and said external extension surface while maintaining its normal position in absence of external displacing forces.

3. In an arrangement for attaching an electric fixture to a wall portion having exposed electric outlet leads, an elongated rod-like fixture extension having teeth on its external surface, and an electric fixture cord extending along said fixture extension; a hollow fixture support extending from said wall portion having an open outward end and interior guide surface portions surrounding said fixture extension; said interior guide surface portions being tapered interiorly in the direction toward the open end of said support; means for detachably and adjustably securing said fixture extension within said hollow support comprising a plurality of segmental gripping members biased to move along said guide surface portions of said support toward its open end and having teeth shaped to interlockingly engage the teeth of said extension and arranged so that said gripping members can be pushed inwardly along said guide surface portions for releasing their interlocking engagement with said extension; the teeth of said extension and the facing teeth of said gripping members being tapered in the directions of the inward and outward motion of said extension within said support; an enclosure carried by said fixture extension for enclosing the space in front of said mounting wall portion and covering the interengaging portions of said fixture extension, said fixture support and the connections between said fixture cord and said outlet leads; and a tubular guard member interposed between the external extension surface and said electric cord for preventing said cord from reaching said external extension surface; said guard member being elastically flexible so that it may be readily displaced

by an external force from its position between the cord and said external extension surface while maintaining its normal position in absence of external displacing forces.

4. In an arrangement for attaching an electric fixture to a wall portion having exposed electric outlet leads, an elongated rod-like fixture extension having teeth on its external surface; a hollow fixture support extending from said wall portion having an open outward end and interior guide surface portions surrounding said fixture extension; said interior guide surface portions being tapered interiorly in the direction toward the open end of said support; means for detachably and adjustably securing said fixture extension within said hollow support comprising a plurality of segmental gripping members biased to move along said guide surface portions of said support toward its open end and having teeth shaped to interlockingly engage the teeth of said extension and arranged so that said gripping members can be pushed inwardly along said guide surface portions for releasing their interlocking engagement with said extension; the teeth of said extension and the facing teeth of said gripping members being tapered in the directions of the inward and outward motion of said extension within said support; and an enclosure carried by said fixture extension for enclosing the space in front of said mounting wall portion and covering the interengaging portions of said fixture extension, said fixture support and the connections between said fixture cord and said outlet leads; the portion of said fixture extension which is clamped between said gripping members in the assembled position of said fixture extension and the adjacent portion of said extension exposed beyond the outward ends of said gripping members being of substantially the same lateral dimensions to permit further inward movements of said extension into the space between said gripping members.

5. In an arrangement for attaching an electric

fixture to a wall portion having exposed electric outlet leads, an elongated rod-like fixture extension having teeth on its external surface; a hollow fixture support extending from said wall portion having an open outward end and interior guide surface portions surrounding said fixture extension; said interior guide surface portions being tapered interiorly in the direction toward the open end of said support; means for detachably and adjustably securing said fixture extension within said hollow support comprising a plurality of segmental gripping members biased to move along said guide surface portions of said support toward its open end and having teeth shaped to interlockingly engage the teeth of said extension and arranged so that said gripping members can be pushed inwardly along said guide surface portions for releasing their interlocking engagement with said extension; the teeth of said extension and the facing teeth of said gripping members being tapered in the directions of the inward and outward motion of said extension within said support; and an enclosure carried by said fixture extension for enclosing the space in front of said mounting wall portion and covering the interengaging portions of said fixture extension, said fixture support and the connections between said fixture cord and said outlet leads; the portion of said fixture extension which is clamped between said gripping members in the assembled position of said fixture extension and the adjacent portion of said extension exposed beyond the outward ends of said gripping members being of substantially the same lateral dimensions to permit further inward movements of said extension into the space between said gripping members; said gripping members having projections extending outwardly sufficiently far beyond the outward end of said support for enabling pushing of said gripping members inwardly to a position in which they release said fixture extension.

ALEXANDER K. SUTHERLAND.
